UNITED STATES PATENT OFFICE.

ALFRED W. FRENCH, OF CHICAGO, ILLINOIS.

SCAFFOLD.

1,270,401.

Specification of Letters Patent. Patented June 25, 1918.

Application filed September 1, 1916. Serial No. 117,985.

To all whom it may concern:

Be it known that I, ALFRED W. FRENCH, a subject of the King of Great Britain, residing at Chicago, in the county of Cook and 5 State of Illinois, have invented a certain new and useful Improvement in Scaffolds, of which the following is a full, clear, concise, and exact description, reference being had to the accompanying drawings, forming 10 a part of this specification.

The object of the invention is to provide an improved portable, adjustable scaffold for supporting a platform or a series of platforms. The invention further aims to 15 lighten the weight of the scaffolding or stagings, decrease the cost of the same and improve the operation and ease of handling.

More specifically my invention provides an improved form of sectional scaffolding 20 which rests upon the ground as a point of support and which is adjustable to any desired height, however great, by adding further sections. This adjustment may be made by the operator while he is upon the 25 platform.

The invention will be fully understood from the following detailed description, together with the accompanying drawings which form a part of the specification, of 30 one embodiment of my invention. In the drawings—

Figure 1 is a perspective view of the scaffolding which is adapted to enter a corner and to be adjustable up and down 35 the side walls as would be required for the decoration of such walls;

Fig. 2 is a diagrammatic, sectional view showing the interior of a building and the manner in which the different forms of scaffolds may be placed in order to make possible work, such as decorating, along both the side walls and the ceiling of the building;

Fig. 3 is a cross-sectional view of one of 45 the posts with a lifting jack mounted thereupon;

Fig. 4 is a top plan view of the lifting jack and post;

Fig. 5 is a side elevation of the same;

Fig. 6 is a horizontal sectional view of a 50 pair of posts and a brace between the posts;

Fig. 7 is a side elevation of the posts and the brace fastening them together;

Fig. 8 is an endwise detail view of the 55 gripping means on the end of the clamp;

Fig. 9 is a perspective view of one of the cross pieces or putlogs between the jack members which travel on the posts and of a bracket supporting the putlog; and

Fig. 10 is a cross-section through the 60 angle iron forming a part of the putlogs.

The scaffolding of my invention is self-supporting as distinguished from the suspended scaffolding which is common in the art.

The question of providing scaffolding for typical operations with respect to buildings such, for instance, as decorating, presents two distinct problems requiring distinct types of construction. One problem is 70 the provision of scaffolding which will enable the decorating of the side walls to be carried on conveniently and expeditiously, and the other problem is to provide scaffolding which will permit the ceiling to be 75 decorated. Any other walls both inside and outside present no distinct problem over the above. For operations on a vertical wall, such as a side wall of a building, I provide the type of scaffolding illustrated diagrammatically in Fig. 1. This comprises essentially the vertical posts or columns 1 which are preferably formed of round iron pipe and rest upon suitable flanges 2 secured to their lower ends. These flanges 2 form 80 cylindrical pedestals of small area. These columns are preferably arranged in pairs between each pair of which is arranged a putlog 3 fastened at each end to a climbing jack 4 which jacks are mounted upon the columns and are adapted to be operated so as to climb up along the column and raise 85 with them the putlogs 3. Suitable braces 5, which are adjustable in length, are connected to the columns 1 of each pair and other adjustable braces 6 are connected to the columns 1 between pairs.

It is obvious that diagonal braces may also be employed—that is to say, braces running diagonally between the posts or columns 1 100 or braces running diagonally between the braces 5 or 6. Suitable boards or planks 7 are laid across adjacent putlogs to form the platform. The ends of the planks are overlapped, as shown in Fig. 1, to form a continuous platform.

The other type of platform, namely that adapted for giving access to a horizontal or substantially horizontal wall, such as a ceiling, is illustrated in Fig. 2. At the right 110

of Fig. 2 is indicated the adjustable type of scaffolding for permitting operation on the side wall 9, this type of scaffolding being that shown in Fig. 1. The remainder of 5 the scaffolding is relatively non-adjustable and is adapted to form platforms for permitting the workmen to operate upon the ceiling 10 and the dome 11. The same type of column or post 1 is employed and the 10 same type of transverse braces 5 and longitudinal braces 6 are also employed. The putlogs 3 in this case are connected to or attached to relatively stationary gripping devices 12, the character of which will be described later, for holding the putlogs in a 15 fixed position. Suitable planks or boards 13 form the stationary platform upon which the workmen and materials are supported. The space between the ceiling 10 and the platform 13 is preferably in the neighborhood 20 of six feet in order to permit a workman to stand upright without bumping his head and still be close enough to the ceiling to work upon the same. In a building where 25 irregularities of the ceiling exist, such as where a dome, as 11, is formed, it is apparent that platforms 14, 15, 16, etc., may be adjusted at such height as to be convenient in carrying on operations.

30 In the case of an intermediate vertical wall it is apparent that jacks 4 and putlogs 3 may be employed for providing a movable platform at such point in the same manner as that illustrated to the right of Fig. 2.

35 The structure of the jack 4 is illustrated in Figs. 3, 4 and 5.

It is to be understood primarily that the corner posts 1 or columns 1 are not continuous pieces of pipe but are sections joined together by suitable couplings, preferably in 40 the manner shown in Figs. 3 and 5. A round pin 15 of substantially the same diameter as the inside of the pipe 1 is secured in the one end of each section as by a rivet 16 or 45 similar means. It is obvious that the plug or pin 15 may be welded to the pipe 1 if desired. The lower end of the next pipe section is left open and forms a socket which fits over the pin or stud 15 with a close, 50 sliding fit so that the walls of adjacent sections, such as 17 and 18, are when in place in effect a continuous length of pipe. The jacks 4 comprise an upper gripping member 19 and a lower gripping member 20. The 55 lower gripping member comprises an outer shell or casing 21. This shell is provided with a pair of lugs or extensions 22, each having an elbow slot 23 therein for receiving and holding the transverse pins 24' at 60 the ends of the putlogs (see Figs. 9 and 10). A pair of rollers 25 and 26 are mounted upon the bolts 27 which pass through the casing 21, and the semi-circular gripping jaws 28 have inclined faces 29 which co- 65 operate with the rollers 25 and 26 to grip

the column 1. The gripping jaws 28 are pressed between the rollers and the columns by means of the springs 30 which rest against the bottom plate 31. The bottom plate 31 is provided with a tubular extension 32, which forms a guide for the holding member 20 to permit easier movement of the same along the column. The inside of the tubular member 32 is recessed or relieved as shown at 33 to make the action 70 smoother. A flanged sleeve 34 lies within the upper end of the shell 21, with the flange lying upon the outside thereof, this sleeve being of such a length as to permit it when pressed downwardly to disengage the gripping jaws 28 from their gripping position between the rollers 25, 26 and the sides of the column. 75

It is to be noted that the inner surface of the gripping jaws 28 is recessed as shown 80 at 35 in order to form a suitable engaging face. The upper gripping member 19 is constructed in a similar manner, this member being provided with suitable lugs 36, to which the ends of a forked lever member 37 are pivoted. The lever member 37 is forked as shown and is provided with a suitable socket 38 into which a short piece of pipe 39 may be inserted to act as a lever. A pair of links 40 are connected at their 85 upper ends to the forked lever member 37 and are connected at their lower ends to the gripping member 20. 90

The putlog 3 is illustrated in detail in 95 Figs. 9 and 10. This comprises a length of 100 angle iron 42 extending over the major distance between the jacks 4 upon adjacent ones of the column forming a pair. An extension member 43, formed also of a piece of angle iron extends the rest of the way. The 105 angle irons 42 and 43 have their adjacent flanges perforated as shown at 44 and 45 to permit of a relative adjustment of the length of the putlogs by means of the bolts 46. Each one of the members 42 and 43 is provided at its outer extremity with a transverse pin 24, as previously explained, which drops into the notch 23 of the adjacent lug 22. The pin 24 is preferably formed as 110 shown in Fig. 10 having a reduced shank 115 portion 47 passing through the one leg of the angle bar and through a collar 48, upon the outer end of which it is riveted.

The braces 5 and 6 are similar in construction, the details of which are shown 120 in Figs. 6, 7 and 8. A suitable length of pipe 49 forms the shaft of the brace and clamping means are provided at each end of the shaft for gripping the column 1. Upon one end of the shaft 49 an engaging piece 125 or saddle 50 is secured as by means of the pin 51, the saddle member 50 being formed with a socket into which the end of the pipe 49 projects.

A U shaped clamping member 52, which is 130

provided with a central hub 53, is mounted upon the pipe 49. The ends of the U shaped member 52 are turned over to form claws as shown at 54, which hook upon the outside 5 of the corresponding column 1 with which this member is in engagement. The arms of the U shaped gripping member 52 are suitably reinforced by ribs or the like to make this member light and at the same 10 time sufficiently strong to secure a firm grip upon the column 1. It is to be noted that the claws 54 are faced in the same general direction, so that the gripping member 52 may be applied to the column by a simple 15 rotary motion. Adjacent spaces of the socket member 50 and of the hub member 53 are cut away to form cam surfaces at 55 and 56, as is clearly indicated in Figs. 6 and 7, and a cam collar 57 lies between the two 20 members and is adapted to force the same apart by working of the cam collar 57 between the hub 53 and the hub of the member 50. The cam collar 57 is provided with a suitable operating handle 58, by means of 25 which the collar may be rotated on the pipe 49 into the position shown in Figs. 6 and 7, forcing the hook member 52 and the saddle member 50 apart in order to grip the column 1. It is thus apparent that the shaft 30 of the brace, that is the pipe 49 is securely gripped to the column 1. The opposite end of the pipe 49 is provided with gripping means for engaging a corresponding column, this particular gripping means being ad- 35 justable on the pipe 49 so as to form a suitable brace between columns of different distances apart.

The pipe 49 passes loosely through the hub 53 of a gripping member 59, which is 40 similar in all respects to the member 52, except that the plane of 29 is inclined to the axis of the pipe 49. Similarly, a cam collar 57, having a handle 58, lies loosely upon the pipe 49 adjacent the hub 53. A 45 clutch member 60 connects the pipe 49 with the adjacent column 1. The clutch member 60 comprises a collar 61 having a pair of ears 62 forming a slot between them, in which slot lies the finger 64 which is piv- 50 oted on a suitable pin 63 passing through the lugs 62. The inner end of the finger 64 is corrugated or roughened as shown at 65 in order to cause the same to bite into and grip the adjacent side of the pipe 49 at the 55 required point to form a secure connection against endwise movement of the pipe 49 with respect to the members 59, 60 and 1. At the same time the pipe 1 is wedged between the fingers 64 and the pipe 49 so that 60 a reliable gripping action is secured. The member 57 instead of being formed with the handle 48 may be provided with a number of sockets 66 and a detachable handle 67 so that the projecting handle will not be 65 in the way. Other suitable means may be

provided for turning the cam member 57 to wedge the parts 53 and 61 or the parts 53 and 50 away from each other.

The operation of the device is as follows: Assuming that the side walls of a 70 building are to be decorated or operated upon, a platform of the general structure shown in Fig. 1 and shown at the right of Fig. 2 is erected. Bottom sections of the columns 1 are first placed in position in 75 pairs at such a distance away from each other as to accommodate a suitable width of platform. Jack members 4 are then placed upon the upper ends of the columns 1 and the putlogs 3 are connected between 80 adjacent pairs of jacks with suitable planks or boards 7 lying across the putlogs and forming the platform. The lowermost braces 5 and 6 are fastened to the columns 1. The right hand end of the brace, as 85 shown in Figs. 6 and 7 is first attached to its corresponding column 1 by moving the handle 58 so that the cam collar 57 occupies the least space between the inclined faces 55 and 56 of the members 50 and 53. 90 The saddle member 50 is placed against the column 1 and the U-shaped gripping member or hook member 52 is hooked upon the outside of the column by a simple rotary motion. 95

The cam member 57 is then rotated as by means of the handle 58 to wedge the members 53 and 50 apart in order to grip the column 1. The other end of the pipe 49 which forms the shaft of the brace lies 100 against the corresponding column 1, and the collar member 61 is moved toward the corresponding column 1 until this column is wedged between the pipe 49 and the finger 64. The corresponding cam collar 57 105 is moved into the position shown in Figs. 6 and 7 and the U-shaped hook member 59 is hooked about the column 1, after which the handle 58 is moved to rotate the cam member 57 thereby forcing the collar 61 110 and the hub 53 apart. The inner end 65 of the finger 64 is forced against the side of the pipes 49 securely gripping the same.

When the platform is to be raised with respect to the side wall a short length of 115 pipe 39 is inserted in the socket 38 of one or more of the jacks 4 and the handle is moved up and down to elevate the corresponding jack. In the drawings of Figs. 1 and 2 I have illustrated the jacks as employing levers of the first class, while in Figs. 3, 4 and 5, I have illustrated the jack members as employing levers of the second class. For the purposes of this application I consider these to be equivalent. In Figs. 120 3, 4 and 5 when the handle 39 is moved upward, the lower gripping member 20 is raised, as is shown in Fig. 3, the weight at this time being carried upon the upper gripping member 19. When the handle is 125

moved downward as is indicated by the arrow in Fig. 5, the lower gripping member 20 remains fixed and the upper gripping member is raised. It will be understood that the opposite set of operations occurs when a lever of the first class is employed as is shown in Figs. 1 and 2.

In order to cause the jaw members 28, which seize the sides of the column when 10 the jack members are operated, from being displaced endwise, relative to each other, I provide a tongue and groove as is shown in dotted line in Fig. 5, at 68.

If it is desired to lower the platform, the 15 handle 39 is worked up and down and at the same time the collars 34 of the gripping members 19 and 20 are alternately depressed to disengage the gripping jaws 28 so that the platform may be suitably lowered, as will be understood by those skilled 20 in the art.

For erecting platforms such as 13, 14, 15 and 16 in Fig. 2, the columns 1 are built up to the desired height by means of braces 5 25 and 6 and by sufficient sections of the columns 1 to bring the platform to the desired height. The members 12 which connect the putlogs for holding the platforms are constructed in substantially the same form as 30 the lower gripping member 20, shown in Figs. 3 and 5. That is to say, the gripping members 12 which support the putlogs are readily adjustable as to height by depressing the flanged collar 34 and lifting or lowering 35 the gripping member as a whole, but after they are once placed they are intended to remain while operations upon the particular wall, namely, the ceiling or dome, are being carried on and completed. It is to be noted 40 that the same columns may serve for supporting the relatively stationary platform and for supporting the movable platform as is illustrated at the right of Fig. 1. As the platform 7 is moved up and down the 45 corresponding braces may require to be disengaged and placed either above or below the platform as it travels or certain sections of the columns may require to be removed, but this can be accomplished with relatively 50 great ease and a minimum loss of time.

In erecting the platforms for the ceiling such as 13, 14, 15 and 16 it is to be understood that climbing jacks may be placed upon the lower sections of the columns 1 55 and the putlogs put in place with planks laid across them and then the whole platform jacked up to the desired height. Thus in certain cases it is easier to build the platform close to the ground and jack the same up rather than pass the planks up to construct the platform at an inconvenient distance above the ground.

In general the columns are placed at the corners of a polygon, particularly a quadrilateral, and putlogs are supported upon

jacks between pairs of the columns. The platform which rests upon the putlogs lies within the quadrilateral and thus any load placed on the platform subjects the columns to compression stresses only. It is obvious 70 that instead of being set at the corners of a quadrilateral the columns may be arranged in any way desired so long as the platform is supported upon putlogs running between pairs of columns.

It is apparent from the above description and the accompanying drawings that a system or scheme of scaffolding of the utmost flexibility and adaptability is provided. It will also be apparent that the spacing of 80 the columns 1 need not be strictly regular or need it be strictly in a quadrilateral pattern. The columns with their interconnecting braces form in effect a trussed tower which is built up from interchangeable stock 85 parts as operations require.

The ability to raise one corner at a time permits a single workman to raise a much greater effective weight on the platform than could be raised by the workman if the platform were to be raised as a whole.

The climbing jacks might, of course, be of any suitable type but I have found that the jacks which I have provided are peculiarly well adapted to the situation. A workman 95 is able to work them by a straight up and down motion which does not tend to make him slip or lose his balance on the platform. Furthermore the jacks are so organized that the lifting effect upon the platform occurs 100 on the downward stroke of the operating handle or lever. Consequently the weight of the workman is taken off the platform at the time the platform is raised and is transferred at that time to the lever. This 105 permits the workman to use his weight at a maximum advantage and to work with ease and a minimum of fatigue.

It will be noted that the slot and pin connection 23 between the climbing jack and 110 the putlog provides a flexible and extensible or lost motion connection which permits one end of the putlog to be raised independently of the other end. It is apparent that the particular location or construction of the 115 extensible or lost motion connection is not important. The operation desired is that the putlog extend from column to column in supporting position and either end of the putlog be independently operable to raise 120 or lower without bending or moving the columns.

It is apparent that numerous changes and modifications in detail may be made without departing from the spirit and scope of my 125 invention.

I claim:

1. A scaffolding comprising four or more columns adapted to form a skeleton tower, parallelogrammatic in plan, put-logs con- 130

necting the columns in pairs and bracing the same as tower elements and forming platform supports, and individual climbing means for each column each connected to 5 one end of the put-log and having a lost motion connection so that either end of the put-log may be shifted vertically a substantial distance independently of the other end thereof, said climbing means being operable 10 from a platform carried by said put-log.

2. A scaffolding comprising four or more columns having braces to form in effect a skeleton tower parallelogrammatic in plan, putlogs connecting the columns in pairs and 15 forming platform supports, and individual climbing means for each column, each put-log being guided along said columns and being supported at its ends by the climbing means and having an extensible connection 20 between columns so that either end of a putlog may be shifted vertically a substantial distance independently of the other end thereof, said climbing means being operable from a platform carried by said putlogs. 25

3. In combination, four columns, a climbing jack on each column, each jack being independently operable from the platform, two putlogs lying substantially parallel to each other and having a lost motion connection 30 with the jacks, a row of planks across the putlogs forming a platform, and removable bracing means below the jacks rigidly interconnecting the columns.

4. In combination, a platform, a series of 35 columns located at the corners of the platform, independently operable climbing means on each column, said climbing means being provided with operating members adapted to be operated from the platform 40 to raise one corner of the platform at a time, putlogs connected at each end to the climbing means and having lost motion connection with the climbing means, said platform being laid across said putlogs, and a series of 45 braces rigidly interconnecting said columns below the climbing means to form a rigid tower for supporting the platform.

5. In combination a pair of round columns of indefinite length, a climbing jack on each 50 column, each jack comprising a pair of gripping members one above the other adapted to grip the column upon the inception of downward movement, a lever fulcrumed at the center to the upper gripping member, 55 said lever having a handle projecting over the platform, a link connecting the outer end of the lever with the lower gripping member, and a putlog connected between the lower gripping members of the jack, said 60 putlog being adapted to support one end of the platform, said putlog having a slidale connection with the attached gripping members.

6. In combination, a plurality of similar 65 upright columns of indefinite length ar-

ranged at the corners of a polygon, climbing jacks on said columns, adapted to grip said columns at any point along their length, putlogs connecting pairs of said climbing jacks, said climbing jacks being all independently operable and having means to permit them to be operated from the platform, said putlogs and jacks being connected together by a telescoping connection permitting relative motion between them but holding them rigidly together and planks lying across the putlogs to form a platform, said platform lying within the closed figure bounded by said columns so that the load on the platform subjects the columns to 70 compression stresses only. 75

7. In a scaffold, a plurality of columns lying in the perimeter of a polygon, gripping means on said columns, a vertically split lug extending from each of said gripping means, said lugs being provided with horizontal slots, putlogs extending between the lugs of pairs of said gripping means, said putlogs comprising each an angle bar having one leg of the angle adapted to lie 80 between the parts of the split lugs and transverse pins passing through the angle bar and lying in the slots of the lugs. 85

8. In a scaffold, a plurality of columns arranged at the corners of a polygon, gripping means on said columns, a split lug extending from each of said gripping means, said lug being provided with an open slot, a putlog extending between a pair of gripping means, said putlog comprising a pair 90 of angle bars having vertical legs adjustably clamped together and having their horizontal legs extending in opposite directions, transverse pins in the outer ends of the angle bars adapted to lie in the open slots of the 95 split lugs. 100

9. A brace for engaging a column, said brace comprising a rod, a forked member having an offset hub member and offset claw members, said rod extending through said hub and past the side of said column, a column engaging member comprising a collar, a lever pivoted on said collar, one end of said lever being adapted to engage the column and the other end being adapted to engage said rod and cam means on the rod between the hub and the collar for forcing the lever into engaging position with respect to said column and said rod. 110 115

10. In combination, a plurality of columns, a jack for each column, a putlog supported between a pair of jacks, a second putlog between another pair of jacks, and a platform supported by said putlogs, said jacks comprising each a pair of gripping members adapted alternately during the operation of the corresponding jacks to grip the column and carry a part of the weight of the platform, while the other gripping member is being moved upwardly, said put- 120 125 130

- 6 logs having a slideable connection to permit of individual operation of each jack without binding the other jack.
11. In combination, a plurality of columns, said columns being placed at the corners of a quadrilateral said columns comprising sections of pipe adapted to be extended vertically indefinitely, braces between said columns, said braces comprising a bifurcated engaging member for engaging one side of the column and a central engaging member for engaging the other side of the column at each end of said brace, cam means between said engaging members for causing said engaging means to press firmly upon opposite sides of said columns and a quadrilateral platform supported at its corners by said columns.
12. In combination, a plurality of columns, said columns comprising sections of pipe extending vertically, braces between said columns, said braces comprising a bifurcated engaging member for engaging one side of the column and a central engaging member for engaging the other side of the column at each end of said brace, and cam means for causing said engaging means to press firmly upon opposite sides of said column, the bifurcated and the central engaging members of one end of each brace being adjustable relative to the length of said brace independently of the cam means.
13. In combination, a vertical column comprising a section of iron pipe, a brace comprising a section of iron pipe held at substantially right angles to said column and lying against the sides of said column, a central engaging member and a bifurcated outer engaging member, cam means on said brace for forcing said engaging members into firm engagement with said column, said central engaging member having means to grip the pipe comprising the brace, said gripping means being controlled by said cam means.
14. In combination, a vertical column comprising a piece of pipe, a transverse brace comprising a piece of pipe, a slotted collar axially movable upon said brace, a bifurcated hook member axially movable upon said brace, a pivoted engaging finger on said slotted collar, said engaging finger being adapted to engage said column and said brace and cam means for forcing said engaging finger into engagement with said column and said brace.
15. In combination, a vertical column comprising a piece of pipe or the like, a gripping member embracing said column, said gripping member comprising a pair of castings, laterally extending lugs on said castings, said lugs having an open slot therein and lying substantially parallel to each other, a putlog between the lugs of adjacent gripping members, said putlog comprising a pair of angle bars having pins at their outer extremities for engaging said slots and means for adjustably clamping said angle bars together.
16. In combination, a plurality of similar upright columns of indefinite length arranged at the corners of a polygon, climbing means on said columns adapted to be supported on said columns at any desired point along their length, put-logs connecting said climbing means, said climbing means being all independently operable and having means to permit them to be operated from the platform, said put-logs and climbing means being connected together upon the columns by a lost motion connection permitting relative motion between them but holding them rigidly in supporting position, and planks lying across the put-logs to form a platform, said platform lying within the closed figure bounded by said columns so that the load on the platform, when the platform is level, subjects the columns to compression only.
- In witness whereof, I hereunto subscribe my name this 30th day of August, A. D. 1916.

ALFRED W. FRENCH.
